UNITED STATES PATENT OFFICE.

HUGO TUECKMANTEL, OF NEWARK, NEW JERSEY, ASSIGNOR TO THE T. & L. CO., INC.,
OF NEWARK, NEW JERSEY, A CORPORATION OF NEW JERSEY.

BAG-FRAME CONNECTION.

Application filed February 16, 1926. Serial No. 88,511.

This invention relates to the frames of bags, satchels, suit cases and similar containers used by travellers, in which a pair of mating metal frames are hinged and provided with a carrying handle.

In the manufacture of such frames it is customary to use for the frame sides rolled strips of right angular cross section and of different sectional area, the inreaching flange of the larger frame side overlying the corresponding flange of the smaller, inner frame side when the bag is closed.

The larger frame side also carries the lock casing and handle affixing means by which the weight of the bag and its contents are supported when carried and if this weight be considerable the effect is to cause separation of the frame sides, tending to distortion and creating an unsightly gap between the upper and lower members of the frame at their upper meeting edges.

It is therefore one of the objects of this invention to provide means whereby such separation is prevented irrespective of the weight carried.

It is a further feature to produce a bag handle clip having integral means to connect with the outer frame member, and further, to secure a keeper element by which the inner frame member is maintained in close relation with the outer member.

Another aim is in the provision of efficient devices for the features mentioned, that are essentially simple and inexpensive to construct and apply, and furthermore, are distinctly ornamental in appearance.

These features are accomplished by the novel construction and combination of parts hereafter described and illustrated in the accompanying drawing, forming a material part of this disclosure, and in which:

Fig. 1 is a fragmentary perspective view of a conventional type of bag in a partially open position, showing an application of the invention.

Figure 2 is an enlarged transverse sectional view of the frame and connected elements, the section being substantially in the plane of the handle loop engaging ring.

Figure 3 is a perspective view of the keeper looking from the base thereof.

The side walls of the bag are designated by the numerals 10 and 11, the material of which is stitched to coverings 12 and 13

completely enveloping the angular frame side members 14 and 15, respectively inner and outer, having inreaching flanges 14' and 15'.

A hollow oblong rectangular casing 16 is pressed from sheet metal to present a closed top 17 at the center of which is a raised transverse ridge 18 having a convex outer surface and containing openings in its ends to receive the registering ends 19 of a round wire loop or ring 20 by which a handle 21 is secured.

The level lower edges of the casing 16 rest on the covering of the larger flange 15', substantially central of its width and the end walls of the casing are provided with elongated prongs 22 which extend through the covering 13 and openings appropriately formed in the flange 15'.

A keeper 23 having offset ends 24 containing elongated openings 25, is held rigidly against the under side of the flange 15', by reason of the prongs 22, which are passed through the openings 25 and bent tightly over the opposite surface of the keeper ends 24, rigidly clamping both the keeper 23 and casing 16 to the outer frame member.

On the outer front surface of the smaller, inner frame side 14 is a flat bar 26 held rigidly by rivet 27, the bar being bent at a right angle inwardly to pass through an opening 28 in the frame member 14 to constitute a flat bolt 29 extending closely below the frame flange 14' and engage, when the bag is closed, within the keeper 23 to contact with its outer and end walls, being guided into engaging position by an outwardly curved lip 30 on the front edge of the keeper.

It will be understood from the foregoing that the bag may be opened or closed in the usual manner with entire ease, and that when closing the bolt 29 is positively guided into the keeper.

As the bolt is rigid with the inner frame and of adequate strength to carry its proportion of the weight with which the bag can be loaded, it will be seen that separation or sagging of one frame side relative to the other cannot occur.

It will be further seen that no unsightly projections appear to disfigure the bag, the covering 12 being disposed over the bar 26 and the protruding bolt 29 is concealed when the bag is closed; it will be apparent

that these devices are used in pairs, one at each end of the handle 21.

Although I have described my improvements with considerable detail and with respect to certain particular forms of my invention, I do not desire to be limited to such details since many changes and modifications may well be made without departing from the spirit and scope of my invention 10 in its broadest aspect.

Having thus described my invention, what I claim as new and desire to secure by Letters Patent, is:—

1. The combination with a bag having a 15 pair of hinged frame members having flanges adapted to fold one within the other, of a keeper having slotted offset ends disposed on the under side of the outer flange, a hollow casing on the top side of the flange 20 to engage a handle, prongs on said casing to pass through the flange and slots in the keeper ends to clamp the casing and keeper thereto, a bar fixed on the face of the inner frame element, said bar being bent to extend 25 inwardly through the wall of the frame below the flange thereof to engage in said keeper.

2. The combination with a bag having a

pair of hinged frame members having flanges adapted to fold one within the other, 30 of a keeper having slotted offset ends disposed on the under side of the outer flange, a hollow casing on the top side of the flange to engage a handle, prongs on said casing, 35 said prongs rigidly engaging in the keeper slots, an inreaching bolt fixed on the inner frame member to engage said keeper, and means for guiding the bolt therein.

3. The combination with a bag having a 40 pair of hinged frame members having inreaching flanges of unlike area, the smaller flange being foldable below the larger, of a handle connection bracket on the larger flange, a keeper under said flange held rigidly by said bracket thereto, said keeper 45 having a depending lip, and a bolt bent to present right angled arms, one of said arms being riveted to the outer face of the smaller frame side and the other to pass through the wall of the frame side, below the flange 50 thereof and be guided by said lip into the keeper.

This specification signed this eighth day of February, 1926.

HUGO TUECKMANTEL.
